CLARENCE S. SNAVELY, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

ELECTRICAL RELAY.

Application filed April 27, 1921. Serial No. 464,989.

My invention relates to electrical relays.

I will describe one form of relay embodying my invention, and will then point out the novel features thereof in a claim.

5 In the accompanying drawings, Fig. 1 is a view showing in vertical section one form of relay embodying my invention. Fig. 2 is a bottom view of the relay shown in Fig. 1, with parts removed to assist in illustrating 10 the structure. Fig. 3 is a top plan view of the relay shown in Fig. 1. Fig. 4 is a fragmental view of the relay shown in the preceding views and illustrating one means for attaching the magnet cores to the top plate 15 of the relay. Fig. 5 is a view showing a portion of the fixed back contact structure included in the relay shown in the preceding views. Figs. 6 and 7 are views showing a modification of the means illustrated in Fig. 20 4 for attaching the magnet cores to the top plate.

Similar reference characters refer to similar parts in each of the several views.

Referring first to Figs. 1, 2 and 3, the relay comprises a top plate A of insulating material, preferably porcelain, which supports all of the operating parts of the device. The armature, contacts, etc. are as usual enclosed in a box which is formed by the top 25 plate A, a base plate 10, and four glass side walls each designated by the reference character 11.

The base plate 10, as here shown, is of metal such as pressed sheet iron or steel, 30 square in configuration, and is provided around its entire periphery with an upstanding flange 10^a. The body of this plate slopes from all four sides toward the center where it is provided with a hole 10^b for purposes 35 of drainage and ventilation, this hole being covered with wire gauze as usual. Attached to the under side of the plate and integral therewith are four supporting feet 10^c, one at each corner.

40 The four glass side walls 11 are located between the under rim of the top plate A and the upper rim of the flange 10^a on the bottom plate, the glass being separated from the plates by means of gaskets 12 and 13 of 45 cork or other suitable material. To hold the glass in place, the plates are clamped together by four machine screws 16 which pass through countersunk holes in the four corners of the top plate A and enter tapped 50 holes in the four corners of the base plate 10.

The relay is provided with an electromagnet which is designated as a whole by the reference character M. This magnet comprises, as usual, two cores 17 of soft iron or other magnetizable material which pass 60 through suitable holes in the top plate A. The lower end of each core is provided with a pole-piece 18 which is integral with the core and rests against the under surface of the plate A. One manner in which the cores 65 may be attached to the top plate is illustrated in Fig. 4. Referring to this view, it will be seen that each core has an enlarged portion 17^a next to the pole-piece 19, and that the upper end of this enlarged portion is provided 70 with screw threads 17^b. The top plate A has two holes 19 designed to accommodate the enlarged portions 17^a of the cores, and each of these holes is countersunk at the top 75 as shown at 19^a. Each core is held in place 80 in the top plate by a sleeve 20 which screws on the threads 17^b and the body of which enters the countersink 19^a, the sleeve being provided with a flange which rests on the upper surface of the plate. After the pole-piece 18 has been drawn tightly against the top plate by turning the sleeve 20, the parts 85 may be locked in place if desired by any suitable device, such as by passing dowel pins through the sleeves and into the top 90 plate.

Again referring to Figs. 1 and 3, each core 18 is provided with a coil 21 of the "form-wound" type, which is slipped over the core after the latter is mounted in the top plate A.

The back-strap of magnet M comprises two sections 22 and 22^a, each having two semi-cylindrical recesses 22^b to accommodate the upper ends of the cores 17, and the two sections are clamped together against the cores by a tap bolt 23. The recesses 22^b are so designed, however, that the two sections do not touch each other when clamped in place, thereby insuring heavy pressure between each section and the two cores 17. One advantage of this construction is that it reduces to a minimum the reluctance of the joint between the back-strap and the cores, and consequently it results in maximum efficiency of the relay in so far as this part of the structure is concerned. Another advantage is that it eliminates the necessity for threading the cores and backstrap; when Norway iron is used the threading operation

is unsatisfactory because the threads do not cut clean owing to the fibrous nature of the material. If desired, a through bolt and nut construction may be substituted for the tap bolt 23 to eliminate the tapping required for this bolt.

The electromagnet M controls an armature 24 which, in the construction here shown, is mounted in pivot pins 25, 25 supported by 10 an armature bracket 26, and which bracket, in turn is attached to the pole-pieces 18 by screws 27. The upward movement of this armature is limited by an adjustable stop 44 which is mounted in the top plate A, safety 15 core pins 45 being provided in the pole-pieces 18 to prevent actual contact of the armature with these pole-pieces in the event that the stop 44 gets out of adjustment. The armature 24 controls a number of contacts 20 which I will now describe.

The reference characters 28 designate contact spring supports, one of which is provided for each contact finger of the relay. This support is made of an insulating material, and is preferably a vitreous substance, such as porcelain. This support is substantially Z-shaped as shown in Fig. 1, but the two legs are not parallel. One leg of the support is attached to the armature by a screw 29, the support being kept in proper alignment by a pin 30 which is seated in the armature and projects into a slot 31 formed in the support 28. The other or free leg of the support carries a contact spring 32 which is perfectly flat and is attached to the support by a screw 33. The shape of the support 28 is such that when the armature 24 is horizontal, the contact spring 32 slopes upwardly at an angle of about 10° as shown 35 in the drawing. Each contact spring 32 coacts with one or more fixed contact members as explained hereinafter.

The contact spring 32 and the means which I have shown for attaching it to the armature 24 have certain features which are of considerable importance. The spring 32 is flat, and is applied to the support 28 without any set or bend, so that there is little or no tendency for this spring to warp. 40 The support 28, being of porcelain or other vitreous substance, is not subject to shrinkage or to distortion. It follows that the calibration of the relay, in so far as the supports 28 and contact springs 32 are concerned, will remain practically without variation throughout the life of the relay.

The free end of each contact spring 32 is provided with a tip 32a of silver, platinum, or other metal which does not readily oxidize under the influence of heat. This tip is preferably formed with a plurality of parallel fingers in accordance with usual practice, and the tip will usually be riveted to the end of the contact spring as shown in 45 the drawings.

In the form of relay shown herein, each contact spring 32 coacts with a fixed front contact member F when the armature 24 is closed, and with a fixed back contact member B when the armature is open.

The front contact member F comprises a block of graphite 34 mounted in a terminal post 36 which in turn is supported in the top plate A of the relay.

The lower or projecting end of the graphite block 34 is wedge-shaped, as shown in Fig. 1, the edge of the wedge being in a horizontal plane and disposed at right angles to the longitudinal axis of the contact spring 32. The operation of the contact 50 is as follows: When armature 24 is open, the contact tip 32a is out of engagement with the block 34. As the armature closes, the tip engages the edge 34b of the block before the movement of the armature is completed, and during the remainder of the movement the tip slides to the left on the edge 34a.

The main advantages of this contact structure are as follows: The face of the 55 metal tip 32a works on practically an edge of graphite, so that any wear which occurs due to rubbing and arcing will reduce the ridge of the graphite block, or the high points thereon if any exist, and so will automatically align the contact edge of the graphite with the contact surface of the spring. This results in lowering the electrical resistance of the contact. Owing to the slope of the graphite surfaces, a very 60 slight amount of wear results in the silver 32a engaging with considerable area of graphite, so that as soon as the "seating action" has taken place, further wear is negligible in so far as its effect on the calibration of the relay is concerned, because of the 65 large amount of graphite which would have to be worn away in order to affect the operation of spring 32. An important feature 70 of the structure is the fact that failure of the armature to close due to pitting of the graphite member is impossible. Another important feature is that the co-efficient of friction of the contact is negligible, so that practically no work is required on the part 75 of the armature in overcoming friction in the contacts. Furthermore, there is no opportunity for the silver tip to lock itself in contact with the graphite member, because of the shape of this member and the 80 angle of spring 32 with relation thereto. The structure retains the advantages of the split finger contact, each finger of the tip 85 32a making individual engagement with the edge of the graphite member.

Any suitable means may be provided for locking the terminal post 36 in place in the top plate A. The device here shown for accomplishing this purpose comprises a washer 38 provided with screw threads 90

matching those on the post 36. The top plate A is provided with a small recess 39 located close to the hole through which the post passes, and which recess is filled with a suitable material, such as lead. To lock the terminal post in place the washer 38 is turned down tight against the upper surface of the top plate and a hole is then drilled through this washer and into the lead in the recess 39. A dowel pin 40 is then passed through the hole and cut off flush with the top surface of the washer 38. This structure makes possible the use of a solid terminal post, and at the same time it secures this post in place in such manner as to prevent tampering with the same without actually showing signs of tampering or destroying the post. The post may readily be renewed in the shop, however, by drilling out the dowel pin and providing a new washer 38. The structure described requires no special construction of the top plate A other than the small recess 39 for accommodating the dowel pin 40.

Each back contact B comprises a brass member 35, shaped as shown in Figs. 1 and 5, and attached to a terminal post 41, which passes through the top plate A. The post 41 is provided with a head 41^a which is drilled and tapped to accommodate a machine screw 42, which in turn attaches the contact member 35 to the terminal post. The contact member 35 is preferably of sheet brass, provided with a tip 35^a of silver or platinum riveted to the member 35, and arranged for engagement with the tip 32^a on contact spring 32.

Referring now to Figs. 6 and 7, I have here shown a modification of the structure illustrated in Fig. 4 for mounting the cores 17 of the electromagnet M in the top plate A. In the form shown in Fig. 6 each core 17 is provided with an enlarged neck 17^c adjacent the pole-piece 18, and the top plate A is provided with countersunk holes 19 to accommodate these enlarged neck portions of the cores. Each core is provided with a collar 43 of non-magnetizable material, such, for example, as brass, the inside of which is reamed so as to be a pressed or forced fit over the neck portion 17^c of the core. To assemble the structure the cores 17 are inserted in the top plate and the collar 43 pressed into place. The initial position of the collar on the core is shown in Fig. 7, whereas the final position is shown in Fig. 6. After the collars have been pressed into place, it may be desirable to either slightly rivet or spin the upper edge of the neck

portion 17^c, as indicated at 17^d, to prevent the collar 43 from rising on the neck piece.

One advantage of this structure is that due to the enlarged neck piece 17^c the reluctance of the magnetic circuit is decreased at the part of this circuit which is not covered by the magnetizing coil 21. This enlarged neck piece also tends to draw the magnetic flux down to the pole-piece, and hence it decreases the leakage as compared with that resulting from a core of thin section in the top plate or a broken or threaded section at this point. It follows, therefore, that the structure shown in these views increases the efficiency of the relay. Another advantage of the structure is that the forming of the core 17 can be accomplished entirely by grinding. Due to the soft and fibrous nature of Norway iron which is generally used for magnet cores, the substitution of grinding for threading and tapping, and also the simplicity of assembly due to the present method, considerably cheapens the production of the relay. Another advantage of the structure is the reinforcing action on the top plate A, as compared with the weakening of this plate when screws are used for supporting the cores.

I do not in the present application make any claim for the following features, these features being disclosed and claimed in a co-pending application, Serial No. 464,988, filed on even date herewith by Clarence S. Snavely and Arthur W. Fisher:

(a) The structure shown for attaching the graphite block 34 to the terminal post 36.

(b) The structure of the relay box comprising the base plate 10 and the glass walls 11.

(c) The structure of the back strap for electromagnet M.

Although I have herein shown and described only one form of relay embodying my invention, it is understood that various changes and modifications may be made therein within the scope of the appended claim without departing from the spirit and scope of my invention.

Having thus described my invention, what I claim is:

A relay comprising a movable armature, a substantially Z-shaped member of porcelain one leg of which is attached to said armature, a flexible contact spring attached directly to the other leg of said insulating member, and a fixed contact element co-acting with said spring.

In testimony whereof I affix my signature.

CLARENCE S. SNAVELY.
